UNITED STATES PATENT OFFICE.

LINDLEY D. HUBBELL, OF HARTFORD, CONNECTICUT.

DESIGN FOR A FRAME OF RADIATORS FOR AUTOMOBILES.

No. 37,827.

Specification for Design.

Patented Feb. 13, 1906.

Application filed July 24, 1905. Serial No. 271,111. Term of patent 14 years.

To all whom it may concern:

Be it known that I, LINDLEY D. HUBBELL, a citizen of the United States, residing in Hartford, in the county of Hartford, in the State of Connecticut, have invented a certain new, original, and ornamental Design for Frames of Radiators for Automobiles, of which the following is a specification, reference being had to the accompanying drawing, forming a part hereof.

This invention consists in the ornamental

design for frames of radiators of automobiles, as shown in the accompanying drawing, which is a view in perspective of a radiator-frame embodying my invention.

I claim—

The ornamental design for a frame of a radiator for automobiles as shown.

LINDLEY D. HUBBELL.

In presence of—

E. A. CULLEN,
L. H. KELTING.
